MACHINE FOR PRODUCING GEARS

Albert P. Schauseil and James E. Gleason,
Rochester, N. Y., assignors to Gleason Works,
Rochester, N. Y., a corporation of New York

Application May 26, 1934, Serial No. 727,771

13 Claims. (Cl. 90—4)

The present invention relates to machines for producing gears and particularly to machines for cutting spiral bevel and hypoid gears. In a still more specific aspect the present invention relates to machines for cutting spiral bevel and hypoid gears without generating roll whether in a roughing or a finish-cutting operation.

One of the objects of the present invention is to provide spiral bevel and hypoid gear rough-cutting and finish-cutting machines of closely similar construction so that standard machine parts and standard machine units may be made up in advance and from these either a roughing machine or a finishing machine may be constructed on order, as may be desired, thereby reducing the manufacturer's inventory for and the costs of both types of machines.

Another object of the invention is to provide an improved form of gear-cutting machine provided with improved means for automatically withdrawing the completed work-piece from operative position at the end of the cutting operation, and with improved means for automatically releasing the chucking mechanism and forcing the completed work-piece off of the chucking arbor when the work-piece is fully withdrawn.

A further object of the invention is to provide an improved machine for rough-cutting spiral bevel gears.

A still further object of the invention is to provide a suitable machine for cutting spiral bevel gears by the face-mill broaching process.

The invention comprises, also, certain other improvements in gear-cutting machine construction which will hereinafter be more fully described and the novel features of which will be pointed out in the claims at the end of the specification.

In the drawings:

Fig. 1 is a side elevation of a spiral bevel and hypoid gear roughing machine constructed according to the present invention;

Fig. 2 is an enlarged view of the work-head end of the machine, parts being broken away and shown in section;

Fig. 3 is a fragmentary end view of the work-head end of the machine showing particularly the indexing mechanism of the machine and the means for operating the same, parts being broken away and shown in section;

Fig. 4 is a fragmentary view of the opposite end of the machine, parts being broken away and shown in section;

Fig. 5 is a horizontal sectional view through the cutter end of the machine showing part of the drive to the cutter and the feed mechanism;

Fig. 6 is a corresponding sectional view taken through a machine constructed according to the present invention for cutting gears by the face-mill broaching process;

Fig. 7 is an elevational view of a cutter such as might be used on the latter type of machine;

Fig. 8 is a transverse vertical sectional view through the work-head of a machine constructed according to the present invention for rough-cutting gears, and Fig. 9 is a corresponding view of a machine constructed according to the present invention for finish-cutting gears;

Fig. 10 is a fragmentary vertical sectional view taken at right angles to Fig. 5 and showing the feed mechanism of the roughing machine there illustrated; and

Fig. 11 is a vertical section corresponding to Fig. 10, showing the modified construction of a machine built according to the present invention for finish cutting.

In both embodiments of the invention illustrated in the drawings, the cutting tool is of the face-mill type. The cutter employed in roughing is preferably of standard face-mill form with blades arranged completely around its periphery, while the cutter employed for finishing is preferably of the circular broach type, as shown in the pending application of James E. Gleason, Serial No. 711,382, filed February 15, 1934, and has cutting blades arranged only part-way around its periphery with a gap between the last and first blades. In both machines, the cutter is secured to a spindle that is journaled in a sleeve that is slidably mounted in an adjustable tool carrier or support, while the gear blank to be cut is secured to a spindle that is rotatably and reciprocably mounted in the work-head. The sleeve, which carries the cutter spindle, is adjustable axially of the cutter spindle to permit setting the cutter to correct cutting depth and to compensate for wear of the cutter after sharpening. The tool carrier is adjustable on the frame of the machine for setting the cutter to cut teeth of the correct spiral angle on the blank and the work-head is angularly adjustable on the frame of the machine for the purpose of positioning the blank in accordance with the pitch cone angle of the gear to be cut.

In the roughing machine, the sleeve, which carries the cutter, is reciprocated to impart an alternate movement of feed and withdrawal to the cutter. During the feed movement, the

work spindle is locked against rotation not only by the locking dog of the index mechanism, but also by a pair of clamping blocks which engage the periphery of the work spindle to hold the 5 spindle positively against rotation. The cutter cuts a tooth slot in the blank on each feed movement. When the cutter reaches full depth position, the feed movement is reversed and the cutter is withdrawn clear of the blank. Then the 10 work spindle is released and indexed. The feed and withdrawal motions of the cutter sleeve, the engagement and disengagement of the clamping blocks with the work spindle, and the operation and lock-up of the indexing mechanism are all 15 controlled by cams which are driven in timed relation with one another and from the same motor that drives the cutter spindle. The cam for operating the index mechanism and the cam for controlling the clamping blocks are, in the 20 illustrated embodiment of the invention, integral with one another, one being a face cam and the other a peripheral cam.

In the finishing machine, the cutter does not have a feed motion. The sleeve carrying the cutter spindle is, as described, adjustable to permit setting the cutter to correct cutting depth, but it is locked against movement after adjustment by a wedge block which is interposed between the sleeve and the cutter carrier. The feed-cam 25 mechanism is, therefore, omitted in building a finishing machine. The same index mechanism is used as in the roughing machine, but the clamping blocks for the work spindle are preferably omitted and the spindle mounted instead 30 in an adjustable three-point bearing. This provides a precision mounting for the spindle and therefore insures greater accuracy in the finished gear.

In the finishing machine, the cam, which 40 operates the index mechanism, is driven in time with the cutter rotation. The cutter has blades arranged part-way around its periphery only as stated above and these blades have successively increasing height up to the full height required 45 to finish the full height of the tooth surface. While the blades of the cutter are passing through a tooth slot of the blank, the blank is held against rotation by the index lock-up dog and, when the gap in the cutter is abreast of the blank, the 50 blank is indexed.

In both machines, at the end of the cutting operation, the completed work-piece is automatically withdrawn from operative position and automatically dechucked. The same mechanism is 55 used in both machines. There is a separate motor mounted on the work-head of the machine. When the automatic stop mechanism of the machine is tripped, this motor is actuated. It drives through a worm and worm-wheel segment, a 60 rocking arm which is connected by a link with the housing for the index mechanism, and the housing and the work spindle, which is movable axially therewith, are forced rearwardly in the work-head, pulling the work-piece out of operative 65 position. At the end of this rearward movement, a lever-arm is tripped to force the draw-rod of the chucking mechanism forwardly in the work spindle to release the work. The head of the draw-rod carries a pin that engages the back 70 of the work-piece immediately after it is released, and starts the work-piece off of the chucking arbor, so that it can be easily removed from the arbor by the operator of the machine.

Reference will first be made to Figs. 1 to 5 inclusive, 8 and 10 of the drawings, which illustrate 75

particularly one embodiment of roughing machine constructed according to the present invention. In these figures, 20 designates the base or frame of the machine. The tool mechanism is mounted in a column or upright 21 that is secured to the base 20. The work spindle 22 is rotatably and slidably mounted in a work-head 23 which is mounted on the base or frame of the machine and is angularly adjustable thereon. The cutting tool, which is here shown as a 10 face-mill gear cutter 25 of known standard construction, is secured to the head 26 of the cutter spindle 27 by bolts 28. The cutter spindle 27 is journaled on taper roller bearings 29 in a sleeve 30 that is slidably mounted in the cutter support or carrier 31. The taper roller bearings 28 and 29 are separated by a sleeve 32 and the cutter spindle 27 is held against axial movement in the sleeve 30 by means of the nut 33 which threads on the spindle and also serves to adjust the bearings. The bearings are protected by a labyrinth seal 34 which is secured to the sleeve 30 by screw 36.

The cutter support or carrier is angularly and slidably adjustable on the upright or column 21 25 of the machine to permit adjusting the cutter as required to cut a gear of the desired spiral angle. As these adjustments are well known and in common use on machines for rough cutting spiral bevel gears, they need not here be described in detail and only a brief description of the mounting of the cutter support will, therefore, be given here. The cutter support 31 is formed at its front end with a flange 38. There is a worm-wheel segment 39 secured to the flange 38 by screws 40. A worm 41 that is journaled in a slide 42 meshes with this segment 39 and is rotatable by hand by means not shown for the purpose of adjusting the carrier 31 angularly about the axis of a pin 44 which is secured by the nut 45 in the slide 42. The cutter support 31 is held in any position of its angular adjustment by T-bolts (not shown) which engage in the arcuate slot 46, and by the gib 47 which is secured to the slide 42 by the bolts 48. The slide 42 is slidably 45 adjustable upon the column or upright 21 by means of a screw 49 (see Fig. 1). The two described adjustments of the cutter carrier 31 permit of adjusting the cutter to cut a gear of any given spiral angle within the range of the machine. 50

The cutter spindle is driven by a motor 50 which is mounted on a bracket 51 that is bolted to the cutter carrier 31 by bolts 52. The motor drives the cutter through the bevel pinion 53 and bevel gear 54, the shaft 55, (Figs. 4 and 5) the spur gears 56 and 57, the shaft 58, the spur pinion 59 and the internal gear 60. The internal gear 60 is secured by screws 61 to a hood 62 which in turn is secured by screws 64 to the head 26 of the cutter spindle 27. A guard 65 is secured by screws 66 to the flange 38 of the cutter support 31 and is arranged to telescope between the internal gear 60 and the guard or hood 62 to protect the gearing against dirt or chips. 65

The alternate movements of feed and withdrawal imparted to the cutter are produced by reciprocation of the sleeve 30 in the cutter carrier 31. These movements are produced by rotation of feed cam 70 (Fig. 10). This cam is secured by bolts 71 to a flanged sleeve 72 which is keyed to the shaft 73 that is journaled on anti-friction bearings 74 and 75 in the cutter carrier 31. The roller 76 engages in the track of the cam 70. This roller is secured in a block 77 by a nut 75

78 that threads on the stem of the roller. The block 77 is adjustably secured to a bracket 80 (Figs. 4, 5 and 10). This bracket 80 has a circular base 81 which is bolted to the end of the 5 sleeve 38 by bolts 82.

The block 77 is adjustable on the bracket 80 in a direction axial of the cutter spindle 27 by rotation of the screw-shaft 85 which is journaled in the bracket 80 and which threads into the 10 block. The block 77 is secured to the bracket 80, after adjustment, by the bolts 86 which thread into the block and pass through elongated slots 87 in the bracket 80.

The cam 70 is driven from the motor 50 through 15 the bevel gearing 53, 54, the shaft 55, the spur pinion 93, the spur gear 91, the shaft 92, the bevel gearing 93 and 94, the inclined shaft 95, the worm 96, and the worm-wheel 97. The worm-wheel 97 is keyed to the shaft 73 and held against axial 20 movement relative thereto by the nut 98.

The roller 76 is held resiliently against one side of the track of the cam 70 to take up backlash, by coil-springs 100 (Figs. 4 and 5). These springs are mounted on plungers 101 and are interposed 25 between a rib 102 of the cutter support 31 and the head of the bracket 80.

The adjustment of the block 77 relative to the bracket 80 is for the purpose of adjusting the cutter 25 to correct cutting depth and compensating 30 for wear of the cutter after sharpening.

The spur pinion 59 and internal gear 60 both have relatively long faces so that they will remain in mesh regardless of the amount of adjustment of the sleeve 30 and throughout the whole of the 35 movement of that sleeve.

The indexing mechanism for the work spindle, which is of the notched plate type, will now be described. 105 designates the index plate. This plate has a number of notches 106, equal to the 40 number of tooth slots to be cut in the gear blank. The work spindle 22 is of reduced diameter at its rear end and the plate 105 is keyed to the reduced portion of the work spindle. The index plate is held on the spindle by the nut 107.

The index plate and with it the work spindle are held against rotation during the feed of the cutter by the locking dog 108 (Figs. 2 and 3) which engages in a notch of the index plate. This dog is secured by screws 109 to a plate 110 45 that is angularly adjustable on an arm 112 about the axis of the work spindle. The adjustment of the locking dog relative to the arm 112 is provided in order to position the blank correctly with relation to the cutting tool. This adjustment is effected by manual rotation of a shaft 113 which is journaled in bearings 114 in a lug 115 that is integral with the arm 112. The shaft 113 carries a worm 116 that meshes with a worm-wheel segment 117 that is integral with the plate 110. The plate 110 is secured in position after adjustment by the clamping-bolts 118 that pass through arcuate slots 119 in the plate 110 and thread into the arm 112.

The arm 112 is pivotally mounted on a pin 120 that is secured in a lug 121 which is integral with the index guard or housing 123.

The dog 108 is constantly urged to locking position by a coil spring 125. This spring is mounted upon a bolt 126 that is pivotally secured to the arm 112 at the free end thereof by the pin 127. The bolt 126 extends through a hole in a lug 128 which is integral with the index housing 123. The spring 125 is interposed between this lug 128 and the washer 129 carried by the bolt. The nuts 55

130 which thread on the bolt allow of adjustment of the tension of the spring 125.

Journaled on a bushing 135 (Fig. 2) which is keyed to the reduced portion of the work spindle, is a rocking arm 136. This arm is held against axial movement by the index plate 105. There is a pin 137 secured in a lug formed integral with the arm 136 (Fig. 3). Pivotally mounted on this pin 137 is a trip dog 138. This dog 138 is adapted to engage a pin 139, which is secured in the arm 112, during the rotation of the arm 136 to rock the arm 112 about its pivot 120 and disengage the lock dog 108 from the index plate 105. The pin 139 is held in the arm 112 by a locking bolt 140.

The arm 136 also carries a pawl 142. This pawl is pivotally mounted upon a pin 143 which is secured in a projection of the arm 136. The pawl has a tooth portion 144 that is adapted to engage in a notch of the index plate 105, after the lock dog 108 has been disengaged therefrom, to rotate the index plate to effect indexing of the work spindle. The pawl 142 is constantly urged toward engagement with the index plate by a spring-pressed plunger 145 that is housed in a bore of the arm 136.

There is a roller 146 mounted on a pin 147 in the tail of the pawl 142. There is a cam surface 148 formed on the arm 112. This cam surface engages the roller 146 and holds the pawl 142 out of engagement with the notched plate 105 as long as the dog 108 is in engagement with the plate 105.

The trip-dog 138 is constantly urged into position to engage the trip-pin 139 by a spring-pressed plunger 149 which is housed in a bore in the arm 136 below the bore which contains the spring-pressed plunger 145.

When the arm 136 is rotated in the direction indicated by the arrow in Fig. 3, the trip dog 138 is brought into engagement with the pin 139 of the arm 112 and this arm is rocked upwardly about its pivot 120 against the resistance of the spring 125. This disengages the lock dog 108 from the index plate 105 and it releases the pawl 142 so that the pawl drops onto the periphery of the plate 105 under actuation of the spring-pressed plunger 145. In the further rotation of the arm 136 in the indicated direction, the tooth 144 of the pawl 142 drops into engagement with that notch 106 of the index plate 105 from which the dog 108 has just been disengaged. As the arm 136 rotates still further in the indicated direction, then, the pawl 142 will rotate the index plate 105 and with it the work spindle, indexing the work spindle. The spring 125 will draw the lock dog 108 down onto the periphery of the index plate 105 as soon as the trip dog 138 has passed the pin 139 and the pawl 142 is in engagement with the index plate. The dog 108 will therefore ride on the periphery of the index plate 55 during the indexing rotation of the plate under actuation of the pawl 142. As soon as the dog 108 registers with the next notch of the index plate, it will drop into that notch. This will bring the cam surface 148 again into engagement with the roller 146 of the pawl 142 and the pawl will be disengaged from the index plate. The indexing operation will have been completed.

The index trip mechanism is reset by reversing the direction of rotation of the arm 136. In the 70 reverse movement, the roller 146 will roll along the cam surface 148, maintaining the pawl 142 out of engagement with the index plate. During reversal, also, the trip dog 138 will rock idly over the pin 139, rotating about its pivot 137.

against the resistance of the spring plunger 149, the pressure on the plunger being less than that produced on the arm 112 by the spring 125.

The adjustable set screw 150 which threads into the arm 136 is provided to limit swinging movement of the trip dog 138 about the pin 131 in one direction to hold this trip dog in position to engage the pin 139 and trip the arm 112.

During the feed movement of the cutter, the work spindle is not only locked against rotation by the lock-dog 108, but also clamped. This is to insure against even the slightest rotational movement of the spindle, thereby to prevent any inaccuracy in the spacing of the teeth of the completed gear. The clamping mechanism comprises a pair of blocks 155 and 156 (Fig. 8) which are mounted to slide in a transverse bore formed in the rib 158 of the work head 23. The two blocks have portions curved on an arc to engage the periphery of the work spindle.

There is a shaft 160 passing through the two blocks and journaled therein. There is a nut 161 threaded on one end of this shaft 160 and between the washer 162 which cooperates with this nut, and the block 156, there is interposed a thrust bearing 164. Adjacent the other end of the shaft there is formed a flange 165 which is provided with a cam surface, as clearly shown in Fig. 8, that is adapted to cooperate with a cam surface formed on the outer end of the block 155.

The shaft 160 is rotated by means of a segment 166 which is keyed thereto. When this segment is rotated in one direction, the cooperating cam surfaces of the flange 165 and the block 155 ride up upon one another and force the blocks 155 and 156 together to clamp the work spindle against rotation. When the segment 166 is rotated in the opposite direction, the blocks 155 and 156 are released to permit free rotation of the work spindle. The blocks are shown in the latter position in Fig. 8.

The indexing mechanism and the clamping blocks 155-156 are operated from a cam 170 (Fig. 3). This cam is provided with two track-ways. One of these track-ways 171 is cut into the periphery of the cam and the other track-way 172 is cut into one end or face of the cam.

There is a roller 174 cooperating with the track-way 171. This roller is carried by a bar 175 that is slidable in a transverse slot 176 formed in the work head 23. The bar 175 carries a rack 177 that meshes with a pinion 178 which is secured to stub-shaft 179 (Figs. 2 and 3).

The shaft 179 is rotatably and slidably mounted in a bearing 180 formed integral with the index housing 123. There is a segment 181 keyed to the shaft 179 adjacent its outer end and this segment meshes with a segment 182 formed integral with the arm 136 above mentioned.

It will be seen that as the cam 170 is rotated, the bar 175 and rack 177 are reciprocated to impart rotational movement first in one direction and then in the other to the gear 178, segment 181, segment 182 and arm 136, to effect indexing of the work spindle and resetting of the index mechanism alternately as above described.

The shaft 179 has a sliding key connection with the pinion 178 so that it can slide in the pinion in the movement of the index housing 123 to loading position, as will hereinafter be described, without the pinion being disengaged from the rack.

There is a lever 185 (Figs. 1, 2 and 3) pivotally mounted at one side of the work head on a pin 186 that is secured in the work head. This lever

carries at one end a stud 187 on which is mounted a roller 188 which engages in the track-way 172 of the cam 170. Segmental teeth 190 are cut into the other end of the lever 185 and these teeth mesh with the teeth of the segment 166 to operate the same and effect movement of the clamping blocks 155 and 156 (Fig. 8), as above described.

The cam 170 is keyed to a transverse shaft 192 that is journaled in a depending portion 193 of the work head 123. The cam 170 is driven in time with the feed cam 70 (Fig. 10) so that during feed of the cutter the index mechanism is locked up by the dog 108 (Fig. 3) and the work spindle is clamped against rotation by the blocks 155 and 156 (Fig. 8) and, when the cutter is withdrawn clear of the blank, the work spindle clamps 155 and 156 are released and the index mechanism actuated.

The drive to the index and clamp-control cam 170 is from the shaft 92 (Figs. 4 and 5) through the bevel gears 195 and 196, the telescoping shaft 197, the bevel gear 198, a bevel gear (not shown) which meshes with the bevel gear 198 and which is secured to a shaft 199, the shaft 199 (Figs. 4 and 2) the bevel gears 200 and 201, the vertical stub-shaft 202, the bevel gears 203 and 204, the telescoping shaft 205, the bevel gear 206, which is secured to this shaft (Fig. 3), the bevel gear 207, the shaft 208, the worm 209 and a worm-wheel (not shown) which meshes with this worm. The worm-wheel is secured to the shaft 192.

The shafts 199 and 202 are journaled in the base or frame of the machine. The shaft 208 is journaled in a bracket or extension 210 of the index housing 123. One part of the shaft 205 is journaled in the base or frame of the machine and the other or telescoping part of this shaft is journaled in the same bracket or extension 210 in which the shaft 208 is journaled. The angular adjustment of the work head for setting the blank to be cut to the correct pitch cone angle is about the axis of the stub-shaft 202 and for this reason, the bracket 212 which carries the forward section of the telescoping shaft 205, is journaled on the bracket 213 in which stub-shaft 202 is mounted, see Fig. 2. The brackets 212 and 213 may be integral with or secured to the base or frame of the machine.

The gear blank G, which is to be cut upon the machine, is mounted upon an arbor 215 (Fig. 2) which may be of any suitable construction to conform to the shape of the gear blank. In the embodiment shown, the arbor 215 is formed with a centering projection which enters the bore of the gear blank and supports the blank. The arbor 215 is secured to a spacing-plate 216 by screws 217 and the spacing-plate is, in turn, secured to the work spindle 22 by bolts 218 and screws 219.

The gear blank is clamped on the arbor 215 by a clamping-plate 220. This plate 220 is held in position by the head 221 of the draw-bar 222 which extends through the bore of the work spindle 22 and is slidably therein.

The draw-bar 222 is constantly urged into chucking position by a coil-spring 224, which is mounted on the bar 222 and which is interposed between the washers 225 and 226. The washer 225 is seated against a shoulder formed internally in the bore of the work spindle 222 while the washer 226 is mounted on the bar 222 and secured thereon by the nut 227. This nut threads on the bar and allows of adjustment of the tension of the spring 224.

There is a thimble 230 mounted with a press-

fit in the bore of the spindle 22 and closing the rear end of the same. This spindle serves as a bearing for a pin or stud 231 which is mounted in alignment with the rod 222 and which has a hardened head 232 at its inner end that engages the rear end of the draw-rod.

The index-housing 123 is closed by a door or guard 235, which may be secured in any suitable manner to the index housing. The door 235 is formed with a rearwardly extending ear 236. Mounted on a pin 237 secured in this ear is a lever 238. This lever is of U-shape in cross-section and between its sides is mounted a rocking lever 240. The lever 240 is pivoted intermediate its ends on a pin 241 that is secured in ears of bosses formed internally on the sides of the lever 238. The lever 240 is provided at one end with a hardened contact tip 242 that is adapted to engage the stud 231. At its other end the lever 240 is formed with a hardened contact tip 243 that is adapted to engage an adjustable stop 245 which is threaded into the index housing 243 and is locked in any adjusted position by the lock-nut 246. The lever 238 is pivotally connected at its free end to a link 247 which is pivotally connected to a lug 248 that is formed integral with the depending portion 123 of the work head.

250 denotes a motor which is suitably mounted on one side of the work head 23. This motor drives a shaft 251 which is suitably journaled in a bracket 252 that is secured by bolts 253 to the side of the work head. There is a worm 255 formed integral with the shaft 251. This worm 255 meshes with a segment 256 which is cut into a rocking arm 258. The arm 258 is keyed to a shaft 259 (Figs. 2 and 8) that is journaled on anti-friction bearings 261 and 262 in the work head 23. A second rocker-arm 264 is keyed to the shaft 259. A link 265 pivotally connects this arm with a rod 266 which is secured by a nut 268 in a boss 269 of the index housing 123 (Figs. 1, 2 and 3).

The index housing is formed with a boss 261 (Figs. 1 and 2) which is held between a shoulder on the work spindle 22 and the bushing 135 that is keyed to the work spindle. Thus, when the index housing is moved, the work spindle 22 will move with it and slide axially in the work head 23. To provide an out-board support for the index housing 123 and to prevent cramping of the work spindle in its axial movement, a rectangular bar 270 (Figs. 1, 2 and 8) is secured to the index housing. This bar is fastened to the housing above the work spindle by bolts 271. This bar slides in a rectangular slot or guide formed in the work head.

The bar 270 is held in the slot, in which it slides, by the section 273 of the over-head tie 60 which connects the cutter end of the machine with the work end of the machine. The section 273 of the tie is bolted to the work head 23 above the bar 270 by bolts 274. The section 273 of the tie is pivotally connected with the section 276 of the tie by a pin 277. The pin 277 is in alignment with the shaft 202 (Fig. 2) already mentioned and the pivot 277 permits of the required angular adjustment of the work head. The section 276 of the tie is secured to the column 21 by bolts 278.

280 denotes an automatic stop mechanism. This stop mechanism may be of any known or suitable construction. The stop mechanism illustrated is that described in the patent to George E. Ford, No. 1,908,626, of May 9, 1933.

With each stroke of the bar 175 (Fig. 3), the stop mechanism is advanced one step. This bar 175 is reciprocated once for each tooth space that is cut in the gear blank so that, when the final tooth space is cut, the stop mechanism is tripped. This stop mechanism 280 is connected electrically with the motor 250 (Figs. 1 and 2) to start the same, as soon as the last tooth space of the blank has been cut.

The motor 250 drives the worm 255 to rock 10 the arms 258 and 264 and move the index housing 123 and work spindle 22 rearwardly through the link connection 265 between the rocker-arm 264 and the index housing. This pulls the work spindle 22 rearwardly in the work head, with- 15 drawing the work-piece from operative position to loading position.

One end of the link 247 is fixed to the work head lug 248. Therefore as the work spindle and the index housing 123 move rearwardly the 20 lever 238 is swung clockwise about its pivot 237 from the position shown in Fig. 2. This carries the contact tip 242 of the lever arm 240 away from the stud 231. It brings the contact member 243 of the lever arm 240, however, closer 25 toward contacting engagement with the stop 245. When the index housing 123 has moved far enough rearwardly to withdraw the work piece to loading position, the stop 245 will strike the contact member 243 and rock the lever 240 30 about its pivot 241, bringing the contact member 242 into engagement with the stud 231 to force the draw-bar 222 forwardly in the bore of the spindle 22 against the resistance of the spring 224 to release the work-piece. 35

There is a stripping pin 290 (Fig. 2) carried by an arm 291 which is secured to the draw bar 222 adjacent the front end thereof. This pin 290 is adapted to pass through a hole in the arbor-plate 215 and strike the back of the gear G to 40 force the gear forward slightly on the hub of the arbor 215, after the gear has been released, so that the operator can readily lift it off. The length of the pin 290 is such that the clamping-plate 220 will have been released by the forward 45 movement of the draw-bar 222 before the pin 290 strikes the back of the gear.

The head of the draw-bar may be of any suitable construction and shape. In the embodiment shown the head of the draw-bar is formed 50 with one or more lugs. The clamping-plate 220 is formed with a corresponding number of slots through which the lugs may be passed when the clamping-plate is rotated so that its slots register with the lugs. Therefore, when the draw-bar 222 has been forced forward to released 55 position the operator can readily remove the completed gear from the work spindle by simply rotating the clamping-plate 220 until its slots register with the lugs of the head of the draw-bar and then slipping the clamping-plate over the head of the draw-bar and then lifting off the gear. 60

The pin 293 shown in Fig. 2 is simply a locating pin adapted to enter a locating-hole in the 65 gear blank to properly locate the gear blank angularly on the work spindle.

When the completed gear has reached loading position and has been dechucked, the operator of the machine may stop the motor 250 or, 70 if desired, this motor may be stopped automatically by operation of the automatic stop mechanism 280 in the resetting of this stop mechanism.

When a new gear blank has been placed on the arbor 215, the clamping disc 220 will be re- 75

placed and the motor 250 will be restarted to return the work spindle to operative position. As soon as the work spindle starts to return to operative position, the contact tip 242 of the 5 rocker-arm 240 will be withdrawn from engagement with the stud 231 and the blank will be chucked by action of the spring 224. When the new blank is in operative position, the motor 250 is stopped and the main drive motor 50 may 10 be restarted to effect the cutting of the new blank.

With but some slight changes, the roughing machine described can be used for finish-cutting gears according to the circular broaching process 15 as will now be described. In the circular broaching process, a cutter 299 of the face-mill type is used, which has a plurality of undersized stock-out blades 300 of successively increasing height followed by one or more finishing blades 20 301 and having a gap 302 between the last finishing blade and the first stock-out blade. This gap is of sufficient angular extent to permit indexing the gear blank while the gap in the cutter is abreast of the blank without withdrawing the 25 cutter from the blank. The cutter 299 is positioned relative to the blank so that the stock-out blades 300 will be the first to cut in a tooth space, and so that the finishing blades 301 will cut to full depth without any relative 30 feed between the cutter and the blank. The feed mechanism of the roughing machine, can, therefore, be omitted from the finishing machine, but the rotation of the cutter 299 in the finishing machine must be timed to the rotation of the index cam 170 so that the index mechanism is operated once for each revolution of the cutter 299, namely when the gap in the cutter is abreast of the blank. The cutter does not have to be withdrawn from engagement with the blank to permit of indexing and the cutter and the blank 35 remain in the position to which they have been adjusted for cutting until the gear is completed. The mechanism for automatically withdrawing the gear from operative position after completion and for automatically dechucking the gear at the end of the withdrawal motion are retained in the finishing machine.

In Figs. 6, 9 and 11 the parts of the roughing machine, which are employed in the finishing machine, are designated by the same numerals which were used in describing the roughing machine.

For adjusting the cutter 299 into proper cutting relation with the blank G (Fig. 6) a screw-shaft 305 is employed. This shaft threads into a nut 306 which is secured in an end-cap 307 that is fastened by bolts 308 to the sleeve 30 in which the cutter spindle 27 is journaled. The end cap 307, nut 306 and screw 305 take the 50 place of the bracket 80, screw 85, block 77, roller 76, cam 70 and the operating parts therefor of the roughing machine. The sleeve 30 does not reciprocate during the cutting operation in the finishing machine. It is only adjusted initially 55 by the screw 305 to position the cutter in correct cutting position. This adjustment can be made very accurately by means of graduated dial 309, that is secured to the screw shaft 305 and reads against a zero mark (not shown) on a ring 310. This ring is secured by screws 311 to a plate 312. The plate 312 is mounted upon a stud 313 secured 60 in a lug 314 of the cutter carrier 31. The plate 312 is clamped against the lug 314 by a nut 315 that threads onto the stud 313.

75 The sleeve 30 is clamped in position after ad-

justment by an arcuate shaped wedge-member 318 that engages the periphery of the sleeve 30 and fits between the sleeve and a tapered part of the bore of the cutter carrier 31. This wedge-member 318 can be forced into clamping position 5 or retracted therefrom by manipulation of a screw-rod 320 that is suitably journaled in the plate 312 and that threads into a lug 321 formed integral with the wedge-member 318.

As shown in Fig. 11 by contrast with Fig. 10, 10 the cam 70, worm-wheel 97, shaft 13 and the bearings therefor can be omitted from the finishing machine. The parts of the machine are protected against dirt and chips by the end-caps 323 and 324. 15

On the work head end of the finishing machine, the same index mechanism is employed as in the roughing machine, but it is preferable to omit the lever 185, rocker-arm 166, and clamping blocks 155 and 156. The thrust of a cutter on 20 the blank in a finishing operation is much less than in a roughing operation because only a very slight amount of stock has to be removed from the gear in the finishing operation and, therefore, it is not necessary to clamp the work spindle 25 as firmly against rotation in a finishing machine as in a roughing machine. In place of the work spindle clamping mechanism it is preferred to substitute in the finishing machine a three-point bearing. This bearing is in the form of a split 30 30 clamp and comprises a pair of tongues or arms 325 and 326 which are integral with the casting of the work head 330 of the finishing machine and have projecting free ends. The section of these tongues or arms 325 and 326 is thin enough 35 so that they may be bent slightly without breaking, to adjust the work spindle 22 bodily. Each arm 325 and 326 has a bearing portion 332 and there is a third bearing portion 333 formed in the casting of the work head at the point where 40 the arms join one another.

The work spindle 22 is centered between the bearing portions 332 and 333 and is journaled therein. The arms 325 and 326 are relieved between the bearing portions 332 and 333 so that 45 only these bearing portions contact with the work spindle. The bearing portion 332 of the arm 325 is adjusted by a screw 335 that threads into a boss 334 formed integral with the work head 330 of the finishing machine. After initial 50 adjustment, this screw remains fixed. Further adjustment of the position of the work spindle is then secured by rotation of the screw 335 which threads into a boss 336 also formed integral with the work head 330. The screw 335 operates on 55 the free end of the arm 326. The screw 335 is locked in any adjusted position by the lock-nut 337. It is accessible at any time for adjustment of the work spindle by removal of the end cap 339 which is secured to a side of the work head 60 by screws 340.

In the finishing machine, the cutter 299 is driven in timed relation with the index cam 170, as stated above. The drive to the cutter is from the motor 50 through the bevel gearing 53, 54, 65 the spur pinion 56, spur gear 57, shaft 58, spur pinion 59 and the internal gear 60 exactly the same as in the roughing machine. The drive to the cam 170 is from the motor 50 through the bevel gearing 53, 54, the shaft 55, spur gears 56 70 and 91, bevel gearing 195 and 196, shaft 197, bevel gearing 198, mating bevel gear (not shown), shaft 199, bevel gearing 200, 201, shaft 202, (Fig. 2), bevel gearing 203, 204, shaft 205, bevel gearing 206, 207, worm-shaft 208, worm 209 and worm- 75

wheel (not shown) Fig. 3, exactly the same as in the roughing machine. The gears of the two trains are simply selected in the finishing machine so that the cam 170 will make a revolution for each revolution of the cutter 299 and the work spindle will be indexed when the gap in the cutter is abreast of the blank. Exactly as in the roughing machine, when the last tooth space of the gear blank has been cut, the automatic stop mechanism 289 will start the motor 250 to drive the worm 255 and rock the arms 258 and 264 and withdraw the index housing 123 and work spindle 22 from operative position. Also, exactly as in the roughing machine, at the end of this withdrawal movement, the lever 240 will be swung to force the stud 231 and draw-bar 232 forwardly in the work spindle to release the clamping plate 228 and force the gear blank slightly forward on centering arbor so that the clamping plate and the completed gear can be easily removed from the arbor.

While the invention has been described in connection with machines for cutting spiral bevel and hypoid gears in a non-generating or forming operation, it will be understood that many of the features of the invention are applicable to machines for cutting gears of other types and to generating machines as well as to non-generating machines. The present application is intended to cover any variations, uses or adaptations of the invention following, in general, the principles of the invention and including such departures from the present disclosure as come within known or customary practice in the machine tool art, and as may be applied to the essential features hereinbefore set forth and as fall within the scope of the invention or the limits of the appended claims.

Having thus described our invention, what we claim is:

1. In a gear-cutting machine, a frame, a sleeve slidable in the frame, a cutter spindle rotatably journaled in said sleeve but held against endwise movement therein, a face-mill gear cutter secured to the spindle, a cam and a cam-roller, one of which is secured to the sleeve, means for rotating the cam to impart endwise reciprocating movement to the sleeve, a work-head adjustably mounted on the frame, a work spindle journaled in the head, means adapted to engage the periphery of the work spindle to clamp the same against rotation during cutting, a pair of cams rotatably mounted on the work-head, means operable by one of said pair of cams for periodical- 55 ly releasing said clamping means, means operable by the other of said pair of cams for indexing the work spindle when released, means for rotating the cutter spindle, and means for rotating the three cams in timed relation.
2. In a gear-cutting machine, a frame, a cutter spindle journaled in the frame, a face-mill gear cutter secured to said spindle and having cutting blades extending part-way around its periphery only with an appreciable gap between the last and the first blades, a work-head adjustably mounted on the frame, a work-spindle journaled in the work-head, means for rotating the cutter spindle continuously, means for holding the work spindle against rotation while blades of the cutter are passing through the blank, and means operable once for each revolution of the cutter to release said holding means and index the work spindle when the gap in the cutter is abreast of the blank.
3. In a gear-cutting machine, a frame, a cutter

spindle journaled in the frame, a face-mill gear cutter secured to said spindle and having cutting blades extending part-way around its periphery only with a gap between the last and first blades, a work head adjustably mounted on the frame, a work spindle journaled in said work head, means for rotating the cutter spindle continuously, means for holding the work spindle against rotation while blades of the cutter are passing through a gear blank, indexing mechanism for the work spindle, a rotary cam controlling the operation of the holding means and the indexing mechanism and operable to release said holding means and actuate said indexing mechanism each time the gap in the cutter is abreast of the blank, and means for rotating said cam in time with the rotation of the cutter spindle.

4. In a gear-cutting machine, a frame, a cutter spindle journaled in the frame, a face-mill gear cutter secured to said spindle, and having blades extending part-way around its periphery only with an appreciable gap between the last and first blades, said blades varying in height around the periphery of the cutter up to the required height of the tooth space as a limit, means for adjusting the cutter spindle axially into operative position so that the cutter will cut to full depth in a gear blank without feed movement axially of the cutter, means for securing the cutter spindle in any position of its axial adjustment, a work head adjustable angularly on the frame, a work spindle journaled in the work head, means for holding the work spindle against rotation while blades of the cutter are passing through the gear blank, and means operable once for each revolution of the cutter to release said holding means and index the work spindle when the gap in the cutter is abreast of the blank.

5. In a gear-cutting machine, a frame, tool mechanism, a work spindle journaled in the frame, means for securing a gear blank to the work spindle, means for adjusting the work spindle and tool mechanism into operative relation, a motor mounted on the frame and operative to actuate the tool mechanism, a second motor mounted on the frame, means operative, when the gear is completed, to start the second motor, means driven by the second motor for separating the work spindle from the tool mechanism, and means operative on the separating movement for releasing the work securing means.

6. In a machine for producing gears, a frame, tool mechanism, a work spindle journaled in the frame, means for securing a gear blank to the work spindle, means for adjusting the work spindle and tool mechanism into operative relation, means for actuating the tool mechanism, means for moving the work spindle axially in the frame to withdraw the work spindle to loading position, and means actuated by the relative movement between the work spindle and the frame for releasing the work securing means.

7. In a machine for producing gears, a frame, tool mechanism, a work spindle journaled in the frame, means for securing a gear blank to the work spindle, means for adjusting the work spindle and tool mechanism into operative relation, means for actuating the tool mechanism, means for automatically moving the work spindle axially in the frame on completion of work on the blank to withdraw the work spindle to loading position, and means actuated by the relative movement between the work spindle and the frame for releasing the work securing means.

8. In a machine for producing gears, a frame,

tool mechanism, a work spindle journaled in the frame, an arbor secured to the work spindle and having a supporting part adapted to enter the bore of the gear to be cut, means for securing a 5 gear blank on said arbor, means for adjusting the work spindle and tool mechanism into operative relation, means for actuating the tool mechanism, means for automatically moving the work spindle axially in the frame on completion 10 of work on the gear blank to withdraw the work spindle to loading position, and means actuated by the relative movement between the work spindle and the frame for releasing the work securing means and immediately thereafter starting 15 the work-piece off of the arbor.

9. In a machine for producing gears, a frame, a tool support and a work support, one of which is movable on the frame to and from operative position, means for securing a work piece to the 20 work support, means for adjusting the two supports into operative relation, means operable automatically, when work on the gear is completed, to move the movable support on the frame to separate the tool and work supports, and means 25 actuated by said separating movement to release the work securing means.

10. In a machine for producing gears, a frame, a sleeve slidable in the frame, a cutter spindle rotatably mounted in the sleeve but held against 30 endwise movement therein, a face-mill gear cutter secured to said spindle, a work spindle rotatably and slidably mounted in the frame, means for securing a gear blank to said work spindle, means for reciprocating the sleeve in the frame 35 to impart alternate movements of feed and withdrawal to the cutter, means for indexing the work spindle during the periods of withdrawal, means for automatically moving the work spindle axially in the frame to withdraw it from operative position when the gear has been completed, and means actuated by the relative movement between the work spindle and frame for 40 releasing the work securing means.

11. In a machine for producing gears, a frame, 45 tool mechanism, a work spindle journaled in the frame, means for securing a gear blank to the work spindle comprising a draw-rod slidable axially in the work spindle and a spring constantly urging said draw-rod into chucking position, index mechanism for the work spindle, a housing 50 for the index mechanism secured to the work spindle against axial movement relative thereto, means connected to said housing for moving the work spindle axially rearwardly in the frame to

withdraw the work spindle from operative relation with the tool mechanism, and a pivoted member operable by the relative movement between the work spindle and frame, on said rearward movement, for moving said draw-rod 5 against the resistance of said spring to release said gear.

12. In a machine for producing gears, a frame, tool mechanism, a work spindle journaled in the frame, means for securing a gear blank to the 10 work spindle comprising a draw-rod slidable axially in the work spindle and a spring constantly urging the draw-rod into chucking position, index mechanism for the work spindle, a housing for the index mechanism secured to the work 15 spindle against axial movement relative thereto, means connected to said housing for moving the work spindle rearwardly in the frame to withdraw the work spindle from operative relation with the tool mechanism, a lever pivotally secured at one end to said housing, a link connecting the other end of said lever to the frame, a second lever pivotally mounted intermediate its ends on the first lever and having one end registering with the rear end of said draw-rod, and 20 means carried by the housing adapted to engage the other end of said second lever to rock the second lever about its pivot when the work spindle is fully withdrawn to inoperative position to cause said draw-rod to be moved against resistance of the spring to release said gear.

13. In a machine for producing gears, a frame, a work head adjustable angularly on the frame, a tool support mounted on the frame, tool mechanism mounted on the tool support, a work spindle journaled in the frame, index mechanism for the work spindle, a housing for the index mechanism secured to the work spindle against axial movement relative thereto, means connected to said housing for moving the work spindle 35 axially rearwardly in the frame to withdraw the work spindle from operative relation with the tool mechanism, a bar of rectangular cross-section secured to the top of said housing to support and guide the work spindle in its movements and 40 slidably in a correspondingly shaped guide-way in the work head, and a brace connected at one end to the tool support and at its other end to the work support and having the latter end overlying said guide-way to retain said bar in said 45 guide-way.

ALBERT P. SCHAUZEIL.
JAMES E. GLEASON.
